UNITED STATES PATENT OFFICE.

HARRY A. WILLS, OF VERGENNES, VERMONT, ASSIGNOR TO JULIA A. WILLS
AND LUCY S. KINGSLAND.

IMPROVEMENT IN MACHINES FOR FINISHING HORSESHOE-NAILS.

Specification forming part of Letters Patent No. 122,876, dated January 16, 1872; reissue No. 5,249, dated January 21, 1873.

To all whom it may concern:

Be it known that I, HARRY A. WILLS, of Vergennes, in the county of Addison and State of Vermont, have invented a new and Improved Machine for Cold-Rolling Horseshoe-Nails; and I do hereby declare the following to be a full, clear, and exact description of the same, reference being had to the accompanying drawing forming a part of this specification:

My invention consists in certain improvements in a machine for cold-rolling horseshoe-nails after they have been formed, to harden and finish them, in which the guide of a feeding-screw that is used to conduct the nails to the pusher, by which they are delivered to the dies, is arranged to change the nails from a vertical to a horizontal position, so that they can be delivered to horizontal dies. Previous to the movement of the device which thus delivers the nails a reciprocating bar carrying a roller-die is caused to advance to the left over the bed-die, for the purpose of acting on a swinging-bar or nail-head holder, and also to enable the roller-die to act as a stop and holding-device for the nails, the same being fed forward, point foremost, beneath it, until their heads come into contact with it. The said head-holder is hung above the bed-die and arranged to come over the head of the nail as soon as the roller-die passes therefrom toward the point, and prevents the nail from bending upward by the action of the roller. The clamping-dies open when the roller-die passes off the point of the nail, the head-holder recedes, and a pusher discharges the rolled nail.

The invention will now be fully described and then clearly pointed out in the claims.

Figure 1 is a plan view of my improved machine with a part broken away; and Fig. 2 is a transverse sectional elevation of the same, taken on the line *x x*, Fig. 1. Fig. 3 is a cross-section through *y y*, Fig. 1.

Similar letters of reference indicate corresponding parts.

A represents a screw-feeder with a vertical guide at *B*, such as have been used before for feeding nails point downward, the nails being placed in the grooves of the screw and between it and the side *B*, and held against fall-

ing through by the heads. Now, in order to utilize this kind of feeding apparatus for delivering the nails horizontally to horizontal dies I provide a scroll-shaped or approximately scroll-shaped lip, *C*, upon the guide *B* under the screw, gradually turning from a vertical line, where the nail first comes against it at *D*, to a horizontal position at *E*, where the screw-thread ends and ceases to act on it, leaving it under a groove, *F*, in the screw for allowing the head to pass under it; or a channel may be formed in the lip for the nail to drop into instead of the groove. *G* is a pusher, which is arranged to work through the vertical part of the guide, to come against the head of the nail when left on the horizontal part of the lip *C*, and push it upon a bed-die or former, *H*, between a fixed die, *I*, and a movable one, *K*, which close laterally against the narrow sides of the nail to hold it on the bed-die for being rolled; also for pressing and smoothing the sides. *L* is the roller-die, mounted at the side and one end of the reciprocating bar *M*, which works under the stationary guide-former *O*, the face of which is the reverse of the upper side of the nail, and carries the roller-die to act with requisite pressure on all parts thereof, beginning at the highest part of the head and rolling down to a point. This roller-die is pushed forward to the left, Fig. 2, before the nail is pushed forward, point foremost, under it by the pusher *G*, until the highest part of the oblique side of the head comes against it. Thus the die acts as a stop for the nails, and likewise holds or presses on them as they are fed under it. *P* is the head-holder, which consists of a short bar of steel pivoted to the stock of the former *O*, and projecting downward to a point above the head of the nail to prevent it from being forced upward by the tendency of the nail to bend under the action of the roller-die. This holder, being fixed on a pivot, *Q*, at the upper end, is pushed forward toward the screw *A* by the end of the bar *M* at the time the nail is being received, or just before, so that the lower end is elevated enough to allow the head of the nail to pass under it freely; but as soon as the roller-die moves back to act on the nail the said lower end is brought on the nail-head by the vibrating arm *Q*, pivoted at *R* to the

movable stock S of the movable die K, and holds the nail from bending upward until the action of the roller-die ceases and it passes off the point; then the die K is withdrawn by a spring, T, releasing the nail both from it and the head-holder P, and it is discharged by a pusher, U.

These devices may be operated by any suitable or approved arrangement of driving-gear; but in this example I have represented a driving-shaft at A', with a train of gears, B', for working the feed-screw; a cam, C', lever D', jointed connecting-bar F', stud G', and a spring, H', for working the pusher; a crank-pin, I', and a yoke for it in the end of the reciprocating roller-die bar M for working it; a cam, K', and the spring T for working the movable clamping die-stock S'; a cam, L¹, push-bar M', and vibrating bar Q for moving the head-holder P back over the head of the nail; and a slotted stud, N', on the bar M' and the curved lever O' for working the pusher, all being arranged as shown in the drawing. The cam L¹ is so adjusted to the crank which actuates the roller-die bar M that the low part L² passes the end of push-bar M' at the time the roller-die is in the forward position over the bed-die, allowing said bar M' to recede and allow the head-holder M to be moved forward by said

die-bar to allow the nail to be pushed in, and the cam C' for actuating the pusher is arranged in such relation to the said crank-pin that the pusher G is actuated to push the nail under the roller-die while the latter is in the said forward position.

Having thus described my invention, what I claim as new, and desire to secure by Letters Patent, is—

1. The combination of the scroll-shaped or approximately scroll-shaped guide B C with the feed-screw, substantially as specified.

2. The combination of the horizontally-acting pusher G with the roller and bed dies, the said pusher and roller-die and the operating devices therefor being arranged in such relation that said die is first caused to advance over the bed-die, and the nail then fed forward, point foremost, beneath the roller-die, until its head comes in contact with it, when the backward movement of the roller-die is commenced, in the manner herein described.

3. The combination of the pivoted or swinging head-holder with the bed-die and roller-die, substantially as specified.

HARRY A. WILLS.
